Specification for Design.

Patented Jan. 1, 1918.

Application filed October 8, 1917. Serial No. 195,462. Term of patent 14 years.

To all whom it may concern:

Be it known that I, CONRAD D. PRUITT, a citizen of the United States, residing at San Francisco, in the county of San Francisco and State of California, have invented a new, original, and ornamental Design for Postage-Stamp-Vending-Machine Cases, of which the following is a specification, reference being had to the accompanying drawing, forming part thereof.

The figure is a perspective view of a postage stamp vending machine case, showing my new design.

I claim:

The ornamental design for a postage stamp vending machine case, as shown.

CONRAD D. PRUITT.
